TOY ACCORDION CONSTRUCTION

Nicholas T. Baldanza, Rutherford, N. J., assignor
to Columbia Protektosite Co., Inc., Carlstadt,
N. J., a corporation of New Jersey

Application July 24, 1948, Serial No. 40,487

9 Claims. (Cl. 84—376)

1

This invention relates to musical instruments and more particularly to an improved toy accordion construction having a simulated piano keyboard octave treble.

Among the objects of the invention is to generally improve toy accordions of the character described which shall provide a construction that readily lends itself to molding the various parts of plastic material, which shall comprise few and simple parts that are readily assembled, which shall be relatively inexpensive to manufacture yet rugged to withstand rough usage, which shall simulate an accordion in both operation and appearance upon which children may learn to play tunes with a minimum of instruction and practice, and which shall be efficient and practical to a high degree in use.

Other objects of the invention will in part be obvious and in part hereinafter pointed out.

The invention accordingly consists of features of construction, combination of elements and arrangements of parts which will be exemplified in the construction hereinafter disclosed, the scope of the application of which will be indicated in the claims following.

In the accompanying drawing in which one embodiment of the invention is shown,

Fig. 1 is a front view, partly in section, showing in detail the interior construction of the bass and treble sections of an accordion embodying the invention.

Fig. 2 is a sectional view taken on the line 2—2 of Fig. 1.

Fig. 3 is an end view of said accordion, showing the exterior of the treble box section.

Fig. 4 is the other end view of said accordion, showing the exterior of the bass box section.

Fig. 5 is a sectional view through the bass section taken on line 5—5 of Fig. 1.

Fig. 6 is a sectional view through the treble section taken on the line 6—6 of Fig. 1.

Fig. 7 is an end view of the treble section, similar to Fig. 3, with the cover removed to show the lever action.

Figs. 8 and 9 are enlarged, fragmentary sectional views taken on lines 8—8 and 9—9, respectively, of Fig. 7 showing the lever mounting.

Fig. 10 is a plan view of one of the reed plates; and

Fig. 11 is a sectional view on the line 11—11 of Fig. 10.

Referring in detail to the drawing, 20 denotes a toy accordion constructed to embody the invention and is seen to comprise a bass section B, a treble section T and a bellows E interposed

2

therebetween and secured thereto so that on relative movement of said sections B and T the bellows E is correspondingly expanded and contracted.

5 The bass section B comprises a box or housing 21 formed with an end wall 21a having spaced openings 21b and concentric arcuate slots 21c. Said wall 21a on the interior side supports a reed plate 24, and has extending through said openings 21b, button headed plungers 25 which cooperate with said reed plate 24 as shown in Figs. 1, 2, 4 and 5.

Box 21 of bass section B may be molded of plastic or other suitable material into an integral unit with end wall 21a having inwardly extending spaced wall portions 21d which form adjoining chambers C. Said wall portions 21d supporting said reed plate 24 to face said wall 21a so as to be interposed between the latter and the bellows E thereby sectionalizing the sound producing effects of said reed plate 24. To retain the latter securely in position a suitable open frame member 26 clampingly fits about the periphery of the reed plate and is attached to the end and side surfaces of wall portion 21d as by suitable lap joints 26a as is clear from Figs. 1, 2 and 5.

To interconnect bass section B with bellows E, said box end walls 21a has spaced side wall extensions 21e which may terminate in a recessed rim 21f for seating and fastening a corresponding shaped border end 27a of the bellows pleated structure 27 in a suitable airtight joint.

If desired integrally formed strap loops 21g and studs 21h may be provided to extend from the exterior of said wall extension 21e as shown in Figs. 1, 4 and 5. Said loops 21g and studs 21h serving as part of means (not shown) for suspending the accordion 20 from the body of the player in the well understood manner.

Each plunger 25 may be molded of plastic with an axial bore 25a positioned toward the reed plate 24 when the plunger extends through opening 21b, the other end of said bore being closed to provide a finger seat or button head 25b for manipulating same. Said plunger may have a radially extending flange 25c of sufficient area to cover the arcuate slots 21c when the plunger is in assembled position with the flange 25c resiliently urged to abut the interior side of said end wall by a suitable compression spring 28 seated in said bore interposed between the plunger bore and the reed plate and as shown in Figs. 1 and 2, forms an air valve stop for chamber C.

Reed plate 24 has a suitable number of pairs of vibrating reeds 24a and 24b, positioned as closures for reed spaces 24c arranged to produce a series of musical tones in diatonic scale. Each reed 24a may consist of a thin elongated flat strip of metal riveted at one end and mounted to lie against one side of said plate 24 and the corresponding reed 24b of like construction is provided to lie against an opposite side of said plate to produce like notes so that one of the reeds of a given pair is actuated by air currents traveling through slots 24c formed in said plate 24 in one direction and the other reeds of such pairs is actuated by air currents traveling through a corresponding slot 24c in the opposite direction, said slots 24c being of slightly less area than the strips forming said reeds. Thus, as is clear from Fig. 5, when the bellows are compressed, reeds 24a may be actuated and when the bellows are expanded reeds 24b may be actuated and reeds 24a are then ineffective.

Treble section T as shown in Figs. 1 and 2 also includes a housing or box 31 which may be made of a single plastic molding similar to bass box 21. Box 31 may be formed with an end wall 31a having spaced openings or air passages 31b and supporting on the interior side thereof reed plate 34.

Said end wall 31a may be formed with inwardly extending spaced wall portions 31d which provide adjoining chambers S. Said wall portions 31d support said reed plate 34 to face end wall 31a so as to be interposed between the latter and bellows E thereby sectionalizing the sound producing effects of the reed plate. It will be noted in Fig. 1 that in treble section T there is provided a single chamber S for each pair of reeds 34a, 34b whereas in bass section B each chamber C serves a plurality of pairs of reeds 24a and 24b. Said reed plate 34 and reeds 34a, 34b are similar in construction to reed plate 24 and reeds 24a, 24b, respectively, afore described. An open clamping frame 36 secures reed plate 34 firmly in position in the identical manner as described above for fastening plate 24 by frame 26 of the said bass section B. Box 31 may also be formed with strap loops 31g and studs 31h corresponding to loops 21g and studs 21h of bass box 21 and cooperating therewith in suspending the accordion as afore described.

Treble section T has a series of double ended or crank levers 41 and as seen in Figs. 7, 8 and 9 may constitute a separately molded unit having a finger key end portion 41a, a valve stop end portion 41b, and an intermediate portion 41c interconnecting said finger key and valve stop portions in an obtuse angular relation. Said intermediate portion 41c may have integrally formed aligned cross studs 41d journaled in open slotted bearing blocks 31e which may be molded as uniformly spaced extensions from the exterior side of end wall 31a as shown in Figs. 8 and 9. Said bearing blocks 31e and studs 41d trunnion levers 41 and also serve as spacers therefor.

To prevent levers 41 from being dislodged from their respective trunnioned open slotted blocks 31e a molded retaining cover or grill 50 has on a rear side adjacent an edge thereof bearing caps 50a uniformly spaced apart to correspond to said open slotted blocks 31e which in the assembly forms a barrier to retain the studs 41d in effective trunnioning position. A support 51 and a brace 51a may constitute a single molded unit which is carried by box 31 through suitable fas-

tening means such as adhesive or by fusing or other means, cover or grill 50 being secured in place to the top of the brace 51a by similar adhesive fastening or by fusing as desired. Said grill 50, brace 51a and an underlying portion of end wall 31a spaced from said grill form an enclosure for the valve stop end portions 41b and blocks 31e, but leaving the finger key end portion 41a exposed to provide a keyboard 55.

Finger key ends 41a of levers 41 may be marked successively 1, 2, 3, 4, 5, 6, 7, and 8 constituting a complete octave, each lever 41 controlling a separate note thereof. In this respect levers 41 differ from plungers 25 since the latter as shown in Figs. 1 and 2 each control more than one note.

When levers 41 are mounted in their respective bearing blocks 31e, their valve stop ends 41b, extending under grill 50, form closures or stops for openings 31b. The finger key ends 41a lie over extension support 51 and are spring pressed in any suitable manner as by leaf springs 52, one spring for each lever 41. Springs 52 are positioned to engage the under-surface of the finger key ends 41a, their normal action being to push finger key ends 41a away from support 51 causing the valve stop ends 41b to bear tightly against openings 31b and more especially against raised rim beads or bosses 31c which surround said openings 31b. Spring 52 may comprise a plurality of separate and spaced independent spring members secured to support 51, or as shown in Figs. 7, 8 and 9 may constitute a plurality of spaced leaves 52a formed of a single spring and extending from a strip portion 52b, the latter being secured to said member support by any suitable means such as batten strip 53.

To simulate the standard keyboard of a conventional accordion a plurality of simulated black keys 54 may be provided in keyboard 55. The finger key ends 41a are cut-out to accommodate said keys 54 which are dummy so that the entire keyboard has the appearance of a professional instrument. These dummy keys 54 may each constitute a separate molding or a single molding joined by means of an integral cross-bar which as shown in Fig. 8 may be batten 53.

The practical application of the invention will now be apparent. After constructing and assembling the parts as described above and shown in the drawing, the instrument 20 may be played in the same manner in which accordions are normally played, namely, by selectively depressing and releasing finger key ends 41a and button heads 25b together or in certain sequences to produce a melody when the bellows B is pumped, that is, when extended or contracted. Pumping the bellows B provides an air flow in either direction through the reed plates 24 or 34 when the openings 31b and arcuate slots 21c, respectively, are open to communicate the respective chambers C and S with the atmosphere at which time the air in passing through slots 24c in the reed plates 24 or 34 will vibrate one of the reeds in the pair depending upon the direction of air flow. Both reeds, in a given pair, are tuned alike so that depressing a given finger key 41a will sound the same note when the air flow is in one direction as when in the opposite direction.

The series of pairs of reeds in reed plate 34 may be tuned to constitute the eight notes of the diatonic scale in a desired key, which in order to correspond to the eight white finger keys of the keyboard may be the key of C major. The series of pairs of reeds in plate 24 may be arranged to constitute three chords in the key of C major, the

pairs of reeds in each chord being positioned to lie in one of the chambers C so that by depressing the appropriate button head 25b, the desired chord will be sounded.

Each finger key note 41a may be designated by numerals such as 1, 2, 3 etc. corresponding to its relative position in the octave to enable a child, who is unfamiliar with reading sheet music, to play melodies simply from a page of printed numerals indicating the sequence of notes constituting a melody. The three chords in the bass likewise may be designated by like numerals or letters (not shown) adapted to the same purpose.

It will now be apparent that only a few molded parts are required, namely, the bass and treble boxes, each being a unitary molded structure, for supporting the reeds and operatively mounting the one-piece levers and the simplified plungers, which are readily assembled into a sturdy construction that will retain effective adjustment capable of withstanding the hard usage as a toy and yet satisfactorily serve as an adequate musical instrument.

It will thus be seen that there is provided an improved toy accordion construction whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A toy accordion having a bass section, a treble section and a bellows interconnecting said bass and treble sections, each of said sections comprising a molded plastic sound box having an end wall formed with inwardly projecting integral wall portions spaced apart to provide adjoining air chambers within each of said boxes, said end wall having an opening communicating each of said air chambers with the atmosphere, reed plates supported by said wall portions one in each box interposed between the bellows and said air chambers, each of said boxes having spaced side wall extensions terminating in an exterior recessed rim securing one border rim end of the bellows thereto in an airtight joint, spring actuated closures mounted directly on said sections for each of said end wall openings, said closures being finger operated for movement free from said openings.

2. A toy accordion as defined in claim 1 in which each of said openings in the bass section end wall is formed with a central circular hole with concentric arcuate slots extending thereabout, a plunger extending through said circular hole and having an axial bore closed at an outer end thereof to provide a button head, said plunger having a radially extending flange of sufficient area to cover said arcuate slots, a compression spring positioned within said bore and bearing against said reed plate to normally urge said flange in position for releasably closing said slots.

3. A toy accordion having a molded plastic treble sound box formed with an extended support and with an end wall having spaced openings communicating a bellows chamber with the atmosphere, a reed plate supported on the in-

terior of said sound box disposed in a plane substantially parallel to said end wall between the bellows and said openings, and closure means for each of said openings including a double ended integrally molded lever terminated at one end with a finger key portion, and at the other end in a valve stop portion, an intermediate interconnecting portion for positioning said finger key and valve stop portions in an obtuse angular relation, integrally formed aligned cross studs projecting from said intermediate portion for trunnioning said lever on said box said end wall having spaced open slotted bearing blocks extending from the outer side thereof for trunnioning said levers thereon, spring means interposed between said finger key portions and said box extended support for normally retaining said valve stop portions in effective position closing said spaced openings, and a grill positioned to extend over said end wall, uniformly spaced apart bearing caps formed on the rear side of said grill to cover said open slotted bearing blocks for retaining the cross studs in trunnioning position.

4. In a toy accordion having a bellows, a bass section connected to said bellows comprising a molded plastic sound box having an end wall, inwardly extending spaced wall portions forming adjoining air chambers within said box, said end wall being formed with spaced circular openings and concentric arcuate slots extending about each opening communicating each of said air chambers with the atmosphere, a reed plate supported by said wall portions interposed between the bellows and said air chambers, and means for selectively opening and closing said slots to permit air flow between the bellows and the atmosphere through the reed plate, said means including a plunger extending through each of said circular openings, said plunger having an axial bore closed at an outer end thereof to provide a button head, a radially extending flange carried by each plunger of sufficient area to cover said slots, and a compression spring positioned within said bore and bearing against said reed plate to normally urge said flange in position for releasably closing said slots.

5. In a toy accordion, a treble section connected to a bellows comprising a molded plastic sound box having an end wall, inwardly extending spaced wall portions forming adjoining air chambers within said box, said end wall being formed with spaced openings communicating each of said air chambers with the atmosphere, a reed plate supported by said wall portions interposed between the bellows and said air chambers, a keyboard support mounted on said sound box, a bracing portion for mounting said support on said box, a double ended integrally molded lever for each of said openings, each of said levers having a valve stop end portion and a finger key end portion interconnected by an intermediate portion in an obtuse angular relation, said intermediate portion having integrally formed aligned cross studs, said end wall having spaced open slotted bearing blocks extending from the outer side thereof for trunnioning said levers thereon, said finger key end portions forming a keyboard overlying said support, a grill positioned to extend over said brace, uniformly spaced apart bearing caps formed on the rear side of said grill to cover said open slotted bearing blocks for retaining the cross studs in trunnioning position, and spring means urging each of said finger key end portions away from said

support for normally retaining said valve top end portions in effective position for closing said spaced openings.

16. The toy accordion as defined in claim 5 including spring means formed with spaced leaves extending to coact with each of said finger ends, and a batten strip for securing said spring means and leaves to said support.

17. The toy accordion as defined in claim 5 including spring means formed with spaced leaves extending to coact with each of said finger key ends, a batten strip for securing said spring means and leaves to said support, dummy keys each integrally formed with said batten strip to lie between adjacent finger key ends, the latter being fitted with relation to said dummy keys for simulating a piano keyboard.

18. In a toy accordion having a bellows, a treble section comprising a one-piece molded plastic sound box having an end wall, spaced wall portions extending inwardly from said end wall forming adjoining air chambers within said box, said end wall being formed with spaced openings communicating each of said air chambers with the atmosphere and side walls extending from the perimeter of said end wall to form a substantially dished structure, said end walls having a recessed rim border for forming a seating joint with said bellows, a reed plate disposed in a plane substantially parallel to said end wall supported by said spaced wall portions, a key board support having a bracing portion mounted on said box, and a grill positioned to extend over

said bracing portion to cover an area of said end wall containing said spaced openings.

19. In a toy accordion having a bellows, a bass section comprising a one-piece molded plastic sound box having an end wall, spaced wall portions extending inwardly from said end wall forming adjoining air chambers within said box, said end wall being formed with spaced openings each having concentric arcuate slots communicating each of said chambers with the atmosphere, side walls extending from the perimeter of said end wall to form a substantially dished structure, said end walls having a recessed rim border for forming a seating joint with said bellows, said spaced wall portions supporting a reed plate disposed in a plane substantially parallel to said end wall.

NICHOLAS T. BALDANZA.
